METHOD AND APPARATUS FOR
GENERATING STEAM

Walter Douglas La Mont, Larchmont, N. Y., assignor to La Mont Corporation, New York, N. Y., a corporation of New York

Application January 7, 1927, Serial No. 159,572

30 Claims. (Cl. 122—1)

This invention relates to methods of generating steam and other vapors and to generators therefor.

In the past it has been proposed to increase the efficiency of steam generators by auxiliary apparatus which serves to heat up the feed water and which may be placed in the stack of the generator furnace or any other suitable point. Economizers of the common type represent a distinct improvement in generator efficiency but they are open to a number of disadvantages. Thus, for example, the circulation of water or other liquid through the tubes is relatively slow, as only the water actually transformed into steam in the steam generator has to be made up by the introduction of fresh amounts of feed water. This relatively sluggish flow renders the economizer elements liable to the formation of scale and when the steam demands on the generator are very variable it sometimes happens that a temporary cessation in steam demand with a corresponding cessation of flow of water through the economizer is not accompanied by a corresponding reduction in the amount of heat applied to the generators and correspondingly the amount of waste heat available to heat the economizer. As a result there is danger of steam locking the economizer elements unless they are placed in a temperature zone so low as to be inefficient.

The present invention has for its object the combination of a liquid heating means performing the function of an economizer with primary vapor generators which combination avoids in part or in whole the disadvantages inherent in economizers hitherto used. A further object of the present invention consists in an improvement of the circulation of primary vapor generators whereby the combination increases the efficiency of the generator, not only by an economizer action but by an actual increase of generator efficiency within the generator itself. Other and further advantages and objects of the invention will be apparent from the following more detailed description taken in conjunction with the drawings which illustrate some typical modifications of the present invention.

Essentially the present invention consists of one or more primary steam generators and an associated auxiliary heating circuit provided with a positive independent circulation from which circulation water is fed to the steam generators in accordance with their demands. In the preferred embodiments of the present invention the pressure in the auxiliary circuit is substantially the same or slightly more than in the steam gen-

erator. I do not claim in this application positively circulated auxiliary circuits in which notable amounts of vapor are generated at a pressure materially higher or lower than that obtaining in the steam generator or generators, this forming part of the subject matter of my co-pending application, Serial No. 115,169, filed June 11, 1926.

While in its broader aspects the present invention is not concerned with any particular type of positively circulated auxiliary heating circuit, in its preferred and more specific embodiments the present invention includes auxiliary economizer circuits in which the water is circulated through the heating elements in the form of a film and in some of the modifications preferably in the form of a film on the inside of tubular heating elements which for brevity will be termed "La Mont film tubes" and which may advantageously embody some or most of the structural features of the La Mont film tube steam generators such as are described in my prior patent, No. 1,545,668, and my co-pending application, Serial No. 32,064, filed May 22, 1925.

Film tube economizers with the extraordinarily high heat transfer which the film principle makes possible, particularly when associated with a suitable arrangement of tubes so as to achieve advantageous gas velocities and hydraulic mean depths, are particularly important in economizer circuits and present in these circuits even greater increases in efficiency than in steam generators, since economizers are commonly operated by means of heat sources at a relatively much lower initial temperature than is the case with steam generators. Accordingly the high efficiency of La Mont film tube economizer circuits permits a very great increase in over-all efficiency since the temperature of stack gases, where the economizer is placed in the stack of a generator, or of other waste heat gases may be reduced to a very low figure.

In the ordinary economizer in which the water is circulated directly in series through the economizer into the generator the object is not to generate steam in the economizer and any steam which may be generated in minor amounts is introduced into the main steam generator. In fact, if a conventional economizer is permitted to generate relatively considerable quantities of steam there is a serious tendency for the tubes to steam lock which may either cause burning out of the tubes or even if this does not occur reduces the heat transfer efficiency of the elements. It is therefore the

practice in common types of economizers to prevent the formation of any considerable amounts of steam.

The positively circulated auxiliary economizer circuits of the present invention may be run on this same general principle, that is, with the object of generating as little steam as possible. With a positively circulated economizer circuit it is, however, possible to separate out steam easily and readily and to unite the steam with that of the main generator or to use it separately. Such a circuit which performs the function of an economizer and an auxiliary generator and which at times may perform solely the one function or solely the other or a combination of both will hereafter be referred to as an "economizer generator circuit" and it is an advantage of some of the more specific embodiments of the present invention that valuable economies can be effected by utilizing economizer generator circuits. This is particularly true when film tube circuits of the La Mont type are used for the reason that with high stack temperatures such as are frequently encountered with common types of mass boiling generators when they are forced to very high ratings, the amount of heat available in the stack gases and which may be absorbed by suitable film tubes is greatly in excess of the amount of heat necessary to heat up the feed water for the steam generator. In such cases, steam may be generated in smaller or larger quantities in a film tube economizer generator circuit and a maximum utilization of the heat of the gases may thereby be realized. Moreover the system is extremely flexible and wide variations in stack gas temperature or volume or both may be taken care of by an economizer generator circuit of moderate size. The constant circulation of water prevents the burning out of tubes and aids in maintaining freedom from scale, and wide fluctuations in stack gas heat content and volume can be taken care of by generating more or less steam in the economizer generator circuit.

The amount of water circulated through the economizer circuits or economizer generator circuits of the present invention may vary within wide limits. The amount of circulation is in most cases a compromise. For maximum thermal efficiency the circulation should be practically no greater than the amount of feed water introduced, so that the water entering the coolest portion of the economizer elements is at a minimum temperature and is thereby capable of abstracting a maximum of heat from the stack gases, particularly where the latter flow over the economizer elements counter to the flow of water in contact therewith, the most efficient and preferred arrangement. It is, however, not possible to take care of considerable fluctuations of feed water demands of a steam generator with a circulation which is so small and if full tubes are utilized the water velocity through the tubes may be insufficient to assure the prevention of steam locking, and to provide for a desirable scouring action to maintain the tubes free from scale. When film tube economizer elements are used the circulation can be very greatly reduced because the travel of the film requires a very much smaller volume of water than is necessary with full tubes. In all cases, however, the circulation must be determined in order to achieve a maximum of safety and thermal efficiency and this invention is not essentially concerned with any definite circulation amounts

which must be determined for each individual case in accordance with the operating conditions encountered in the particular installation.

When full tube economizer circuits or economizer generator circuits are utilized they will in general maintain a pressure substantially the same as that in the main generator or rather slightly in excess so as to effect feeding. When, however, film economizer circuits are used it is usually not practical to maintain a pressure in the economizer elements themselves which is equal to that of the steam generator unless the economizer is also a generator of considerable amounts of steam. Accordingly, in the ordinary film tube economizer circuit of the present invention suitable valves must be provided in conjunction with the circulating pump or other device, so that while the pressure in the economizer elements themselves and in many cases throughout the connections between the elements and the suction of the pump, is much lower than that obtaining in the steam generator and may in fact be but little, if any, above atmospheric pressure, the pressure in the portion of the circuit from the discharge of the pump to the film elements is equal to or usually slightly in excess of that of the steam generator. This can be effected by suitable throttle valves in the circulating connections and in some extreme cases may be maintained by the drop in pressure through the film element injection nozzles or orifices, although, for most purposes, this drop in pressure is insufficient and is difficult to regulate.

The maintenance of the proper pressure and the amounts of water fed from the economizer circuit into the steam generator or in the case of a plurality of generators into the different generators, can be effected by manual control or by automatic control or by a combination of the two. I prefer, in most cases, to provide suitable water levels in the film economizer elements or their connections and in the steam generator and operate their valves controlling the amount of water fed from the economizer circuit into the generator and the pressure in the pump discharge circuit from these various levels. It will be clear to the skilled engineer that a very large number of possible control modifications can be used to bring about this effect. Some arrangements which I have found to be desirable in certain cases are illustrated in the drawings but it should be clearly understood that the invention is in no sense limited to these particular control arrangements and, on the contrary, any suitable control may be used and the proper control or combinations of controls will be determined by the skilled engineer in each particular instance, taking into consideration the operating conditions which obtain.

Film economizer circuits, according to the present invention, in which the pressure existing in the film elements and in the connections between the film elements and the suction of the pump is considerably lower than that obtaining in the steam generator, present a very important advantage. In the first place, the suction of the circulating pump is not under great pressure and the problem of suitable stuffing boxes to prevent leakage is greatly simplified and where the pressure is not greater than that of the atmosphere, practically nonexistent.

The same lower pressure permits the introduction in this portion of the circuit of relatively

large drums or other vessels without excessively heavy construction. While it is an advantage to keep the actual circulation through the film elements at a very low amount when compared to the amount of feed water introduced there is a distinct advantage in providing a satisfactorily large reserve volume in the circuit to take care of sudden fluctuations in demand. This can be done simply in film economizer circuits by means of relatively thin walled drums or other storage reservoirs which can be inserted in the low pressure portion of the circuit. The large volumes of water which may thus be retained in the circuit without decreasing its thermal efficiency also renders it a simple and easy matter to separate the impurities from the feed water by well known purification processes. It is an added advantage therefore of film tube economizer circuits that simple and reliable means for removing solids from the feed water can be incorporated in them without the necessity of expensive structure.

The advantages of low pressure in a portion of the economizer circuit are particularly simply and easily obtained with film economizer circuits. It should be understood, however, that a similar advantage can be obtained in full element economizer circuits although not as readily. The invention therefore includes circuits having zones of low pressure, irrespective of whether the circuits utilize film elements or full elements.

In the general description which has been given above film elements and full elements have been discussed as two sharply divided and qualitatively different systems. As a matter of fact, however, there is no absolutely sharp line since, if the amount of water introduced into the top of an element is gradually increased the film which first forms will increase in thickness until the element approaches a condition in which it is difficult to determine whether it is a full element or whether a true film exists for the full length of the tube element. Thus, for example, as the amount of water introduced into a tube is gradually increased, the tube may be full for a short distance from the top and the water may then gradually form a film. The present invention is therefore not limited to two definitely demarcated types of economizer circuits and includes any positively circulated economizer circuit whether film or full element or some intermediate condition.

The combinations which are possible particularly with economizer generator circuits render the present invention extremely flexible in its application, particularly to installations operated by a plurality of heat sources which may be intermittent or fluctuating and also installations in which a very variable steam demand is present. Such combinations automatically adjust themselves to varying demands and maintain a high thermal efficiency throughout. Economizer circuits of the present invention may be associated with any known types of steam generator, whether film tube, water tube, fire tube or flash, and this wide range of applicability is one of the advantages of the invention.

The invention will be described in greater detail in connection with the drawings, in which

Figure 1 is a diagrammatic section through a film tube generator and economizer generator situated in the same stack;

Figure 2 is a similar section of a modified type of film tube generator and film tube economizer having series gas flow;

Figure 3 illustrates a film tube generator and separately heated economizer;

Figure 4 illustrates a vertical water tube boiler with an economizer in the stack;

Figure 5 illustrates an inclined water tube boiler with an economizer in the stack;

Figure 6 illustrates a combination of a positively circulated water tube generator and a common type of water tube generator having convection circulation;

Figure 7 illustrates the combination of two separate water tube boilers associated with a single economizer circuit;

Figure 8 illustrates the combination of a water wall, a common type of water tube generator and a fire tube economizer;

Figure 9 illustrates the application of an economizer circuit of the present invention to a common type of water tube generator and feed water heater; and

Figure 10 is an enlarged sectional detail of a header and a portion of a tube showing the injection orifices.

In the constructions shown in Figure 1, a conventional type of film tube generator is shown having upper headers 1, lower headers 2, tubes 3, a pot 9 and a pump 4. The circulation is from the pump 4 through the pipe 5 into the upper headers 1 which are provided with orifices as shown in Figure 10 whence the water flows in the form of film down through the tubes 3 into the lower headers 2 and into the pot 9 where steam is separated and taken off through the pipe 6 provided with a control valve 7 and excess water is returned to the pump through the pipe 8.

The economizer which is located in the stack above the film tube generator consists in upper headers 11, lower headers 12, tubes 13, pot 19, pump 14 and circulating pipes 15 and 18 connecting the pump with the upper headers 11 and pot 19 respectively. A steam take-off from the pot 19 is effected through the pipe 16 provided with a control valve 17, the pipe joining the main steam pipe 6. The water circuits of the economizer and the generator are connected through the pipe 21 which leads from the pipe 15 to the pipe 8 and is provided with a control valve 22. Feed water for both systems is introduced into the pipe 15 through the pipe 23 provided with a control valve 24. The pots 9 and 19 are provided respectively with water level controls 10 and 20 which in turn actuate the valves 22 and 24.

In operation water is circulated through the generator circuit by means of the pump 4, steam being generated and passing off through the pipe 6.

At the same time water is being circulated through the economizer circuit by means of the pump 14, the pressure of the two circuits being substantially the same. Obviously, of course, the pressure in pipe 5 is slightly higher than in the pipe 8 to compensate for the pressure drop through the orifices in the upper headers 1 and correspondingly the pressure in the pipe 15 is slightly in excess of that in the pipe 18. As the water level falls in the pot 9 and connecting pipe 8, the water level control 10 operates to open the valve 22, permitting water from the pipe 15 to flow into the pipe 8 and therefore into the circulation of the generator circuit. This results in a lowering of the water level in the pot 19 of the economizer and the associated pipe 18 and causes the water level control 20 to operate the valve 24 introducing feed water into the pipe 15, whence it is circulated through the headers 11 and tubes 13 and is heated by the gases passing up the stack.

The economizer circuit may be run either as a straight economizer or as an economizer generator by opening or closing the valve 17. If the circuit is run with the tubes 13 full of water it is possible to run the circuit either as a straight economizer or as an economizer generator. If, however, the headers 11 are provided with injection orifices as shown in Figure 10 and the circuit is operated as a film tube circuit the valve 17 is preferably permitted to remain open and the circuit then operates as an economizer generator, any steam generated being separated in the pot 19 and passing through the pipe 16 into the pipe 6, where it mixes with the steam from the main generator.

The pressure maintained in the pipe 15 by the pump 14 is such that all of the feed water has to pass through the tubes 13 before it enters the main generator circuit and is therefore warmed up, abstracting a corresponding amount of heat from the gases passing over the tubes 13. The temperature of the water entering the headers 11 is kept at a minimum as it is cooled by the incoming feed water for both circuits and it is therefore possible to reduce the temperature of the stack gases to a very low point with correspondingly high over-all efficiency. Wide fluctuations in firing and in the rating under which the main generator operates are easily taken care of, as even if the rating is increased to the point where the stack gases are very hot, the economizer generator can readily take care of the extra heat by the evolution of an increased amount of steam which is added to that of the main generator and utilized.

It should be understood that Figure 1 and the other drawings in this application are purely dia-grammatic and many structural features and accessories which are unnecessary to show the novel methods of operation of the present invention have been omitted for the sake of simplicity. Of course, in actual installation such suitable structural features and accessories, such as safety valves, blow-offs and the like will be included. In general, the film tube generators and economizer generator circuits shown in Figure 1 may be provided with any of the structural features or accessories which are described and illustrated in my prior patent and application above referred to.

As the temperature of the heating gases decreases they shrink in volume and it is desirable in many cases to reduce the gas passage correspondingly in order to maintain high velocity which is desirable in effecting efficient heat transfer. In the drawings this effect has been achieved by decreasing the spacing of the tubes 13 in the direction of gas flow. Obviously, of course, a similar arrangement can be utilized in connection with the tubes 3 and in general such modifications of the structure and arrangement of the generators as may prove desirable are included in the present invention.

In Figure 2 a film tube generator and associated film tube economizer is shown, but no provision is made for generating and separating any considerable volumes of steam in the economizer circuit. Similar elements bear the same numerals as in Figure 1. Instead of providing a steam outlet from the pot 19 of the economizer both the water and any steam which may be formed pass through the pipe 18 connecting pot 19 with the pump 14. In this pipe 18 is the large tank 25 where impurities introduced by the feed water may be separated. The pressure in the economizer tubes themselves is very much lower than

that in the main generator and accordingly a suitable throttle valve 26 is provided in the pipe 15 in order to reduce the pressure to a suitable point.

This construction presents numerous advantages. In the first place it is possible to provide a large settling tank 25 of relatively cheap construction since it is under a comparatively low pressure and may even be at atmospheric pressure or below. A relatively light and inexpensive construction is thereby made possible. In the same manner, the problem of keeping the stuffing box of the pump tight is practically eliminated due to the low pressure. A further advantage lies in the fact that since the pressure in the elements 13 is very much lower than in the main generator, the water temperature is correspondingly low throughout the full length of the tubes and therefore the stack gases can be reduced to an exceedingly low temperature and in general to a considerably lower temperature than is possible when economizer generators are run at the same pressure as the main generator as illustrated in Figure 1.

A modified feed control is shown, the water level 10 not only controlling the valve 22 but also the feed valve 24 which introduces feed water into both systems. Obviously, of course, a separate water level can be provided on the tank 25 for controlling the valve 24, as is shown in Figure 1. In fact, either method of control can be used in connection with either system and any other suitable control method may be substituted therefor. In this respect the drawings are not intended to limit the invention but merely illustrate a number of suitable modifications.

In Figure 3 a separately heated economizer circuit is shown, the type illustrated being connected to a source of intermittent waste heat such as, for example, a water gas plant, a suitable valve 26 being provided to control the heating gas flow. The economizer generator circuit is connected to the main generator circuit in the same manner as in Figure 1 and the same parts are designated by the same numerals. A very efficient utilization of waste heat is made possible by the fact that whenever the waste heat gases flow through the economizer generator their heat is absorbed and efficiently utilized either in the form of sensible heat of the water introduced into the main steam generating circuit or in the form of steam when the amount of waste heat is sufficient to raise steam. Wide fluctuations in amount and duration of waste heat are easily taken care of by the arrangement shown which is very flexible and is applicable to a number of different types of installation.

Instead of waste heat a separately fired economizer may be used and in certain cases is advantageous. Thus, for example, a cheap fuel, such as, for example, low grade coal slack or breeze can be used, requiring a steady even firing and the main steam generator may be fired by powdered coal or oil or some other source of heat which can be varied rapidly. The relatively low temperature which is produced by firing the low grade fuel is effectively utilized as the economizer generator circuit may be efficiently operated at very low ratings.

A single separately heated economizer generator circuit may be associated with a single main generator or a plurality of economizer circuits may be associated with a single generator or a single economizer circuit with a plurality of generators. The most satisfactory and efficient ar-

arrangement will be determined in any case by the skilled engineer and the present invention is not in any sense limited to the particular arrangement shown.

Figure 4 illustrates a combination of a positively circulated economizer generator with a vertical water tube boiler of the Wickes type. The Wickes boiler, which is of conventional design, consists in an upper drum 27, lower drum 28, front water tubes 29, rear water tubes 30 and a baffle 31. The circulation in the Wickes boiler is the usual convection circulation and is ordinarily downward in the tubes 30 and upward in the tubes 29. Steam is separated in the drum 27 passing out through the pipe 32 controlled by the valve 33.

The economizer which is placed in the stack is of similar design to that shown in Figure 1, consisting in upper headers 11, lower headers 12, pot 19 and tubes 13. The steam space of the pot 19 is connected to the steam space of the drum 27 by means of the pipe 16 provided with a check valve 34. Water from the pot 19 passes through the pipe 18 into the pump 14, whence it is circulated back to the upper headers 11 through the pipe 15. Feed is introduced into the pipe 15 near the upper headers 11 by means of the pipe 23 controlled by the valve 24, which is in turn actuated by the water level control 20 operating on the water level in the pipe 18 and pot 19. A valve 35a is also provided in the pipe 15 when it is desired to run the economizer as a film tube economizer without generating steam. The circulation in the economizer circuit is precisely the same as that described in Figure 1 and any steam generated mixes with the steam in the Wickes boiler. The check valve 34, however, takes the place of the manually adjustable valve 17 in Figure 1, and prevents back flow of steam from the Wickes boiler to the economizer circuit, should the latter at any time be at a lower pressure.

Feed is introduced into the Wickes boiler from the pipe 15 through the pipe 36, controlled by the valve 37, which is in turn actuated by the water level control 38 operating on the upper drum 27. Preferably, the pipe 36 is carried into the drum 28 and discharges directly into the bottom of the tubes 29 in order to effect a maximum improvement of circulation in the Wickes boiler. In many cases it is desirable to provide the pipe with nozzles which actually project into the tubes 29.

In operation, water is circulated through the economizer circuit either in a full tube or film tube condition and any steam which is generated passes off through the pipe 16 and check valve 34 into the drum 27. When the economizer circuit is operated as a film tube economizer generator, the operation is the same. When, however, it is operated as a film tube economizer without generation of steam the pressure normally in the tubes 13 will be lower than that which obtains in the Wickes boiler and accordingly it is necessary to introduce a pressure transformer between the junction of the pipes 15 and 36 and the upper headers 11 in order to permit the maintenance of a higher pressure in the pipe 36 than that which obtains in the tubes 13. A simple throttle valve 35a can be used as pressure transformer or any other suitable device may be substituted.

The feed into the Wickes boiler is controlled by the water level control 38 which determines the amount of water fed from the pipe 15, whereas the feed into the economizer circuit is controlled by the water level control 20, the control arrangement being similar to that shown in Figure 1.

It should be noted that the invention is not limited to the particular arrangement of controls and other devices which are illustrated in the drawings. Thus, for example, in Figure 1 a manually operated valve 17 is used to control the steam output from the economizer generator circuit, whereas in Figure 4 a check valve 34 performs a similar function. Obviously, of course, a check valve can be used in the modification shown in Figure 1 and a manually operated valve in the 10 modification shown in Figure 4, or a combination of manually operated and check valves may be used in either case. Other methods of control may also be utilized such as automatic control of valve 35a.

The arrangement shown in Figure 4 is an unusually efficient arrangement since it renders practical operation of the Wickes type of boiler at relatively high ratings which would otherwise be very wasteful owing to the fact that the Wickes type of boiler cannot ordinarily be forced to high ratings without very serious stack losses. The highly efficient arrangement of economizer elements serves to absorb the heat of the stack gases, even when unusually high ratings are necessary. A serious disadvantage of the Wickes type of boiler is thus overcome and the present invention makes it possible to utilize Wickes boilers for purposes for which they were but poorly suited. A further advantage of the modification shown is that it can be embodied in existing installations with a minimum of rebuilding, thus making possible the economic utilization of the old installations which had outgrown their usefulness and also makes it possible to carry peak loads economically with boilers which had been designed for much smaller loads. Gas velocity is maintained throughout the whole economizer by progressive decrease in size of the gas passages to make up for shrinkage due to cooling.

In the modification illustrated a single economizer is associated with a single generator but obviously, of course, one economizer may be used to take care of a number of generators.

Figure 5 illustrates an economizer circuit associated with inclined tube water tube boiler of conventional design. The boiler consists in a drum 37, front headers 38, rear headers 39 and tubes 40, pipes 41 and 42 connecting the drum to the headers 38 and 39 respectively. Steam is taken off through the pipe 43 controlled by the throttle valve 44. The circulation is of the usual convection type.

The economizer circuit is similar to that shown in Figure 2 and the corresponding parts bear the same numerals. In operation, feed water is introduced through the pipe 23 controlled by the valve 24 which is actuated by the water level control 20 and is circulated by means of the pump 14 through the tubes 13, the pressure being reduced by the pressure transformer 26 which is situated in the pipe 15. The film tubes or elements 13 therefore operate at a very low pressure which may be but little, if any, above atmospheric pressure. It is thus possible to reduce the temperature of the stack gases to an exceedingly low figure and a relatively large settling tank and water reservoir 25 can be provided without entailing expensive construction. The low pressure also renders the problem of tight stuffing boxes in the 70 pump 14 relatively simple.

Water for the water tube generator is fed through the pipe 45 which connects the pipe 15 with the pipes 42. A suitable control valve 46 is provided in the pipe 45 and is actuated by a water

level control 47 operating on the drum. The advantages of a low pressure in the heating elements of the economizer circuit shown in Figure 5 are, of course, the same as those described in connection with Figure 2. Similar economizer circuit arrangements are possible with other common types of boilers and only one or two typical boilers are shown in the drawings, the invention not being limited thereto nor to the particular combination shown. Thus, for example, in Figure 4, an economizer generator circuit is shown associated with a Wickes type boiler, whereas in Figure 5 a straight film economizer circuit is shown in connection with an inclined tube water tube boiler. Obviously, of course, a lower pressure economizer circuit can be associated with a Wickes type boiler or an economizer generator circuit with an inclined water tube boiler such as that shown in Figure 5. In general, the particular type of economizer or economizer generator circuit to be used in any particular installation will be determined by the skilled steam engineer in accordance with the operating conditions and structural features of the installation.

25 In the foregoing figures special forms of economizer circuits resembling La Mont film tube generators in their general arrangement have been shown. For many, if not most purposes, this general type of economizer circuit or economizer generator circuit is the most suitable and constitutes the preferred form. Other types of positively circulated economizer circuits may, however, be used and in some cases present advantages. Such an arrangement is shown in Figure 35 6, where a single pass Edgemoor boiler is shown redesigned to give a positive circulation and acting as an economizer generator in association with a Ladd type water tube boiler.

The Edgemoor boiler consists in an upper steam drum 48, lower drum 49, generating tubes 50, rear drum 51, return circulation tubes 52 and pump 53. The tubes 52 unite in a header 54 which is connected to the suction of the pump 53 by the pipe 55. From the discharge of the pump 53 the pipe 56 connects to the drum 49. The circuit is completed by the pipes 57 and 58 which join the steam and water spaces respectively of the drums 48 and 51. The pipe 56 is provided with a control valve 59 actuated by a water level 60 which operates on the drum 48. A conventional design of superheater and feed water preheater or economizer is shown associated with the Edgemoor boiler. This preheater consists of pipes 61 which join headers 62 and 63, feed water being introduced through the pipe 64 into the latter header and the heated water, together with any steam formed passing into the drum 51 through the pipes 65. Saturated steam from the drum 51 may either be taken off directly through the pipe 66 controlled by the valve 67 or in usual operation is passed through the pipe 68 into the header 69 of the superheater and thence through the superheater tubes 70 and out into the superheating steam pipe 71.

65 A conventional Ladd type water tube boiler is shown consisting in upper drum 72, lower drum 73 and three sets or bundles of tubes 74, 75, and 76 with associated baffles 77 and 78. As is usual in the Ladd type construction the lower drum 73 is divided into a large chamber 79 and a small chamber 79a by the baffle 80, the tube bundles 74 and 75 connecting the upper drum 72 with the space 73, whereas the rear tube bundle 76 connects the space 79a with the upper drum. Feed water is introduced from the discharge of the

pump 53 through the pipe 81 into the space 79a of the lower drum. A control valve 82 is provided in the pipe 81 and is actuated by a water level control 83 operating on the upper drum 72. The circulation in the Ladd generator is the usual convection circulation in the tube bundles 74 and 75. Feed water passes up through the bundle 76 into the upper drum aiding this circulation.

The combination of a single economizer generator circuit with two common types of water boiler is shown in Figure 7. The two boilers illustrated are a bent tube boiler of the Stirling type consisting in upper drums 84, 85, and 86 and a lower drum 87 which is connected to the upper drums by the tube bundles 88, 89 and 90 respectively. Steam and water spaces of drums 85, and 86, are connected by pipes 91 and 92 respectively. The second generator is a conventional type of cross drum inclined tube water tube boiler consisting in a steam drum 93, tube headers 94 and 95, collector drum 96, generating tubes 97 and return tubes 98, the drums 93 and 96 being connected with the headers 95 and 94 by the pipes 99 and 100, respectively. Steam is taken off in the usual manner from the drums 86 and 93 by steam pipes not shown. The gas circulation through the generators is indicated by the arrows and induced draft is produced by two stack fans 101 and 102 respectively, which discharge into ducts 103 and 104 provided respectively with control dampers 105 and 106. The two ducts join into a single stack 107 in which a film tube economizer generator is located. The generator consists in an upper collector header 108, upper headers 109, lower headers 110, tubes 111 and a pot or collector 112. Circulation is downwardly from the lowest point of the pot 112 through the pipe 113 to the pump 114, whence the water passes up through the pipe 115 into the upper collector header 108. Feed is introduced into the pipe 115 from the pipe 116 controlled by the valve 117 which is in turn actuated by a water level control 118 operating on the pipe 113. Any steam generated is separated in the pot 112 and passes off through a steam pipe 119 controlled by a valve 120.

Feed water for the two water tube generators is taken from the pipe 115 through the T 121 and pipes 122 and 123 provided respectively with control valves 124 and 125 which are in turn actuated by the water level controls 126 and 127 operating on the drums 85 and 93 respectively.

In operation each of the water tube generators can be separately fired and operated independently, the amount of feed water introduced being constantly controlled by the respective water level controls. The waste heat in the stack gases from the two generators is efficiently utilized in the economizer generator circuit which generates steam at substantially the same pressure as the two generators, which steam may be, if desired, mixed with the steam from the two main generators. At the same time, feed water for all three systems is introduced into the pipe 115 and thence into the top of the elements 111. As a result the temperature of the water entering the top of the tubes or elements 111 is very low owing to the relatively large proportion of feed water to water circulated from the pump 114. A very efficient utilization of the stack heat is thereby assured.

The draft through the water tube generators is controlled by the dampers 105 and 106 and in fact the whole operation of the water tube gen-

erators is substantially independent although if desired the generators may be fired together. Two different types of water tube generators have been shown arranged in a battery but obviously the generators may be of the same type and a much larger number may be associated together with a single economizer generator circuit. In fact, the present invention finds one of its most important fields of utility in conjunction with 10 batteries of common type generators which in many cases are provided with a common stack. The preferred form of economizer generator circuit which resembles in many of its structural features the La Mont type of film tube generator, 15 is particularly suited for such types of installation as the long narrow tubes can be easily and readily placed in the stacks which provide draft for the batteries and it is an advantage that in the case of old installations the economizer generator circuits of the present invention can be installed 20 without radical rebuilding.

Figure 8 illustrates a combination of an economizer circuit using a fire tube economizer with a water tube steam generator and with a water wall 25 generator associated therewith. The water wall generator is of the positively circulated type as described in my copending application Serial No. 32,064, filed May 22, 1925, and is not claimed in the present application apart from its combination 30 with an economizer circuit.

The generator consists in an upper drum 128, lower drum 129 and tubes 130. A second steam drum 131 is connected to the lower drum through the return pipes 132. A circulation pipe 133 connects the steam space of the drum 128 with the steam space of the drum 131, and serves to permit the circulation both of steam and water. The design of the generator is similar to that of the well known Edgemoor single pass generator.

10 The furnace walls are protected by water walls consisting in upper headers 134, 135 and 136, lower headers 137, 138 and 139 and tubes 140, 141 and 142. The furnace is provided with four water walls, only three of which are shown in the drawings. Water is circulated through the tubes by means of the pump 143 which takes water from the various lower headers through the pipe 144 and distributes water to the upper headers through the branched pipe 145. Steam and water discharged from the lower ends of the water wall tubes are separated in the lower headers 137, 138 and 139, and the steam passes off through the branched pipe 146 which connects with the steam pipe 147 from the drum 131. The pipe is provided 55 with a suitable valve 148.

In the stack of the furnace a fire tube economizer is placed, consisting of a shell 149, upper head 150, lower head 151 and fire tubes 152. A perforated plate 153 is mounted a short distance 60 below the upper head 150 and fits loosely around the fire tubes, so that substantially annular orifices are formed between the tubes and the plate. The economizer is thereby divided into a small upper water chamber between the head 150 and the plate 153 and a larger main chamber between the plate 153 and the lower head 151. In this lower chamber a water level is maintained by means of the water level control 154 operating on the valve 155 in the feed water line 156. If desired, the water level may be maintained in tank 158 instead of in the main chamber. Water is circulated from the water space of the economizer through the pipe 157 into a slow point or treatment tank 158 and thence by the pump 159 through the pipe 160 into the upper water cham-

ber of the economizer. The water in this upper chamber then trickles down through the annular orifices forming a film on the outside of the fire tubes and the advantages of high heat absorption which are provided by the film, are obtained. Any 5 steam generated passes off through the pipe 161 either into the main steam pipe 147 or into a separate pipe 162, the former being provided with a valve 163 and the latter with a valve 164, while a third valve 165 is placed in the pipe 161 between 10 the two outlet pipes. It is therefore possible to pass the steam from the economizer either out through the pipe 162 or into the pipe 147 or part through one pipe and part through the other, as may be required by the particular operating conditions. 15

Feed water for the water tube boiler is taken from the pipe 160 through the pipe 166 into the lower drum 129, a branch pipe 167 carrying water to the pipe 144 in the water wall system. This 20 latter pipe may advantageously be provided with a valve 168 controlled by a water level control 169 operating on any of the lower headers of the water wall, and shown for example, in the drawings as operating on the lower header 139. A 25 similar control of feed can be used in connection with the water tube boiler.

In operation, feed water for all three systems is taken into the economizer circuit through the pipe 156, is heated in the economizer with or 30 without the generation of steam, purified by the settling or treating tank 158 and then forced by the pump 159 through the economizer circuit and also into the circuits of the water tube boiler and the water wall system. The economizer circuit may be run at the same pressure as exists in the water wall boilers and in the water tube boiler or a lower pressure may exist in the actual heating elements of the economizer circuit. This can be effected by partially closing the thro'tle 40 valve 170 which is situated in the pipe 160. When, of course, the pressure in the economizer is lower than in the other two generators any steam generated must be permitted to pass off through the separate pipe 162, which can be 45 effected by a suitable operation of the valves 164 and 165. Operating the economizer at a lower pressure than that obtaining in the generators is frequently highly advantageous since it is thus possible to use a much lighter construction of 50 economizer and treating tank than would be possible if high pressures were used and at the same time, the lower pressure with corresponding lower temperature in the economizer permits the reduction of the stack gases to a temperature which 55 is considerably lower than that possible when the economizer is run at the same pressure as the main generator. This effects a notable saving in heat, particularly when the main generator and the water walls are run at very high ratings 60 which would normally result in a considerable heat loss due to high stack gas temperatures.

Figure 9 illustrates a simple application of an economizer circuit of the present invention to an inclined water tube boiler of common type 65 provided with a feed water heater. The boiler consists in a drum 171, front tube headers 172, rear tube headers 173 and tubes 174. Suitable baffles 175 are placed to bring about an even gas velocity, the passage cross-section decreasing in 70 the direction of the gas flow to compensate for the shrinkage in heating gas volume.

An economizer generator comprising upper headers 176, lower headers 177 and tubes 178 is placed in the stack and the heating chamber 75

is progressively decreased in cross-section in the direction of gas flow in order to maintain uniform velocity in the steadily shrinking gas stream.

- 5 Water and steam from the lower headers 177 are discharged into the tank 178 through the pipe 179. From the bottom of this tank, water is fed into the rear header 173 of the generator through the pipe 180, pump 181 and pipe 182.
- 10 The pump is driven by an electric motor or steam turbine 183 controlled from the water level 184 on the drum 171. Steam which is separated in the tank 178 passes out through the valved pipe 185 provided with a check valve 186. The economizer circuit may be operated at the same pressure as the generator in which case the steam from the pipe 185 may be passed into the boiler lead 187 through the pipe 188, the combined output passing through the main steam pipe 189 controlled by the throttle 190 and finally entering the high pressure stage of a turbine 191.

A feed water heater 192 provided with the usual trap 193 and filtering layer 194 is arranged so that it takes the overflow from the tank 178 through the valved pipe 195. Feed water is introduced through the valved pipe 196 and introduction is controlled by a water level 197 operating on the feed water heater. Steam is bled from the intermediate pressure section of the 30 turbine through the pipe 198 into the feed water heater where it heats up the incoming water. The water from the lower portion of the feed water heater is forced by the pump feed 200 through the pipe 199 into the upper header 176 of the economizer circuit.

Under normal operation, the feed pump 200 runs at constant speed and continuously circulates water through the pipe 199 into the economizer which may be of the full tube, film tube, 40 or any intermediate type. The suction of the pump 200 is constantly provided with a water head by the water level control 197 which determines the amount of feed water input. The water passing through the economizer tubes 178 is heated and may generate steam at a pressure equal to that of the generator or at a lower pressure. When operating at the same pressure, with the steam pipe 185 connected through the pipe 188 to the steam line of the main generator, 45 the check valve 186 prevents back-flow of steam and insures even operation. The water separated from the steam in the tank 178 is fed in varying amounts into the main generator, the rate being varied by the speed of operation of the pump 181, which is, in turn, controlled by the water level in the drum 171. Normally, the pump 200 is set to deliver sufficient water to take care of the maximum feeding rate of the pump 181, although this is not essential. Whenever the 50 feeding rate of the pump 181 drops below the rate at which water flows into the tank 178, the water level in the latter rises and overflows into the feed water heater where the water may be further heated together with the cold incoming feed by means of the steam bled from the turbine. Thence, the partially heated water is again circulated through the economizer. The amount of steam bled from the turbine may be 55 controlled by the valve 201 which may advantageously be an automatic valve and may be controlled by the water level control 197 or by the pressure in the feed water heater or by 60 thermostatic means.

The installation illustrated in Fig. 9 represents 75 a very simple means of utilizing installations

which are already in use and which may be provided with feed water heaters. A minimum of rebuilding or redesigning is necessary. Where new installations are made, it is usually unnecessary to provide a feed water heater as the economizer due to its higher efficiency is usually sufficient to supply the adequate amount of pre-heating. Wherever desired, however, a feed water heater may be associated with economizers of the present invention.

In Figs. 1 to 8, the control of feed into the main generator is usually shown as effected by the opening and closing of a valve in the piping from the economizer circuit to the generator. In Fig. 9, however, the control is shown as effected by variation of the speed of the pump feeding the generator and a similar method may be utilized in connection with the other modifications shown in the other figures of the drawings. The drawings are intended to illustrate a number of possible control modifications, but, of course, they cannot exhaust the field of practical combinations, and it should be clearly understood that the invention is not limited to the precise details and arrangements set forth in the various figures.

In the figures, regulation of feed has been by opening and closing valves or by varying the speed of a pump. Control may also be effected by intermittent operation of the circulating pump of the economizer circuit, that is to say, when the 30 feed demand ceases, the pump can be caused to stop and when demand again rises, the pump starts up again. Combinations of pump speed control and valve opening may, of course, also be used and are covered in the invention.

The invention has been illustrated in connection with a number of common types of boilers which are only a few illustrations of a number of possible combinations. The invention is in no sense limited in its utility to combinations 40 with the generators shown. Thus, for example, instead of the water tube or film tube generators which have been illustrated, the economizer or economizer generator circuits of the present invention may be associated with many types of 45 fire tube boilers and such combinations present marked advantages for certain uses.

The preferred type of economizer circuit in which the water is circulated through the heating elements in the form of a film at a pressure 50 which is relatively low and which permits the provision of settling and purifying tanks of economical construction is not limited in its usefulness to generators of the water, film or fire tube type. On the contrary, the possibility of far reaching 55 purification by physical or chemical means renders this type of economizer advantageous for use in connection with flash boilers where the scaling problem is sometimes also serious. A further advantage of the preferred modification lies in 60 the fact that the relatively large treatment tanks which are possible when the pressure is low permit the support of considerable volumes of water. This is of importance where the feed into the generator is intermittent as the economizer can 65 continue to run and abstract heat from the gases, the heat being stored in the volume of water contained in the economizer circuit. Where the economizer circuit also generates steam, the steam automatically constitutes a heat storage. It is an advantage of the preferred modification of the present invention that heat is abstracted 70 from the stack gases continuously even though the feed into the generator may vary in amount or may be intermittent.

1. What is claimed as new is—

1. Apparatus for the generation of steam comprising in combination, a steam generator, an auxiliary circuit, said auxiliary circuit containing heating elements, means for circulating water positively and continuously through said elements in amounts insufficient to completely fill said elements but greater than the amount which can be evaporated in said elements under maximum heating conditions, means for feeding water from said auxiliary circuit into the generator, and means for introducing feed water into the auxiliary circuit.

2. Steam generating apparatus comprising in combination a steam generator, a positively circulated auxiliary circuit, means for feeding water from said auxiliary circuit to the generator, means for introducing feed water into said auxiliary circuit, a water level in said generator, a water level in said auxiliary circuit, means operated by the generator water level for controlling the feed of water from the auxiliary circuit into the generator, and means operated by the water level of the auxiliary circuit for controlling the introduction of feed water in the auxiliary circuit.

3. Steam generating apparatus comprising in combination a steam generator, an auxiliary circuit, said circuit including heating elements, means for positively and continuously circulating water therethrough in amounts insufficient to fill the elements but greater than the amount of water which can be evaporated by passage therethrough under maximum heating conditions, means for maintaining a high pressure in at least a portion of the auxiliary circuit between the circulating means and the heating elements, means for maintaining a relatively low pressure in the heating elements and in the connections from the elements to the circulating means, water treating means located in said low pressure portion of the circuit, means for feeding water from said high pressure portion of the circuit into the steam generator, and means for introducing feed water into the auxiliary circuit.

4. Steam generating apparatus comprising in combination a steam generator, an auxiliary heating circuit, comprising heating elements, means for positively and continuously circulating water through the heating elements, means for separating any steam generated in said elements, means for feeding water from said auxiliary circuit to the water circuit of the steam generator, connecting means from the steam space of the steam separator in the auxiliary circuit to the steam space in the steam generator, means for permitting steam to flow from the auxiliary circuit to the steam generator but preventing counter-flow, means for maintaining a lower pressure in the heating elements of the auxiliary circuit than that which obtains at the discharge of the circulating means, and means for introducing feed water into the auxiliary circuit.

5. Steam generating apparatus comprising in combination a steam generator, an auxiliary circuit in which are included economizer elements, a pump for circulating water through said circuit, means for insuring positive distribution of the water to each element and a connection from said auxiliary circuit to the generator whereby water is delivered thereto under action of said pump.

6. Apparatus for the generation of steam comprising in combination a steam generator, a positively circulated auxiliary circuit including econ-

omizer elements, means for limiting the quantity of water introduced into said elements to amounts insufficient to completely fill them and means for feeding water from said circuit to the generator.

7. Steam generating apparatus comprising in combination a steam generator, an auxiliary circuit, said circuit including heating elements, means for positively and continuously circulating water therethrough, means for maintaining a high pressure in at least a portion of the auxiliary circuit between the circulating means and the heating elements, means for maintaining a relatively low pressure in the heating elements and in the connections from the elements to the circulating means, water treating means located in said low pressure portion of the circuit, means for feeding water from said high pressure portion of the circuit into the steam generator, and means for introducing feed water into the auxiliary circuit.

8. A vapor generator heated by heating gases, economizer elements arranged in the path of said heating gases, means for introducing feed into one end of each element in amount normally insufficient to fill the elements, and means for introducing unevaporated liquid from the other ends of the elements into the generator, said means including a pressure transformer whereby the economizer elements may be operated at a pressure different from that obtaining in the vapor generator.

9. Steam generating apparatus comprising in combination a steam generator, a positively circulated auxiliary circuit including economizer elements, means for supplying water to said elements and for insuring positive distribution thereof to each individual element and means for feeding water from said auxiliary circuit to said generator.

10. Steam generating apparatus comprising in combination a steam generator, an auxiliary circuit, said circuit including heating elements, means for positively circulating water therethrough, means for maintaining a high pressure in at least a portion of the auxiliary circuit between the circulating means and the heating elements, means for maintaining a relatively low pressure in the heating elements, and means for feeding water from said high pressure portion of the circuit into the steam generator.

11. Steam generating apparatus comprising in combination a steam generator, an auxiliary circuit connected therewith, said circuit including heating elements, headers supplying said elements and having jet orifices whereby the water is circulated through the elements in amounts insufficient to fill them but greater than that which can be evaporated in passing through the elements under minimum heating conditions, said jet orifices also maintaining a high pressure in at least a portion of the auxiliary circuit between the circulating means and the receiving ends of the heating elements, and means for maintaining a relatively low pressure in the heating elements.

12. Steam generating apparatus including a steam generator and an auxiliary circuit including economizer elements, means to feed water to the circuit and from the circuit to the steam generator, and means for insuring the positive distribution of the water to each of the economizer elements and its passage therethrough prior to its introduction into the generator.

13. Steam generating apparatus according to

claim 12 in which a pump circulates water through said auxiliary circuit and elements in one direction and in which the feed water is introduced into the circuit between the pump and the elements and beyond the point in the circuit where water is fed therefrom to the generator.

14. Steam generating apparatus comprising in combination a steam generator, an auxiliary circuit in which are included heating elements subjected to the heat of a lower heat zone than that of the steam generator, means for circulating water through said elements in amounts insufficient completely to fill said elements but greater than the amounts which can be evaporated therein in passage of the water therethrough, and means for delivering to the steam generator water from said auxiliary circuit.

15. Steam generating apparatus comprising in combination a steam generator, an auxiliary circuit in which are included heating elements subjected to the heat of a lower heat zone than that of the steam generator, means for circulating water through said elements in amounts insufficient to fill the elements but greater than the amounts which can be evaporated therein in passage of the water therethrough, means for maintaining a relatively high pressure in at least a portion of the auxiliary circuit between the circulating means and the heating elements, means for maintaining at least in the heating elements a relatively low pressure, and means for delivering water to the generator from said high pressure portion of the circuit.

16. Steam generating apparatus comprising in combination a steam generator, an auxiliary circuit in which are included heating elements subjected to the heat of a lower heat zone than that of the steam generator, means for circulating water through said elements in amounts insufficient to fill the elements but greater than the amounts which can be evaporated therein in passage of the water therethrough, means for maintaining at least in the heating elements of the auxiliary circuit a pressure relatively low with respect to the pressure in the steam generator, and means for delivering water to the steam generator from said circuit.

17. A vapor generating apparatus comprising a vapor generator, an auxiliary heating element, means independent of the vapor generator for introducing from a source outside the vapor generator into one end of the element the liquid to be vaporized, means for limiting the water as it enters the element to an amount insufficient to fill the cross-sectional area available for flow through the element, and means for delivering to the vapor generator unevaporated liquid from the other end of said element.

18. A vapor generating apparatus comprising a vapor generator, an auxiliary heating element, means independent of the vapor generator for introducing into one end of the element the liquid to be vaporized in an amount insufficient to fill the element but greater than can be evaporated therein in passage therethrough, means connected to the other end of the element for separating from the liquid any vapor formed in the passage of the liquid through the element, and means for delivering to the vapor generator the unevaporated liquid.

19. A vapor generating apparatus comprising a vapor generator, a plurality of auxiliary heating elements, means independent of the vapor generator for introducing in parallel into the elements at one end of each thereof the liquid to

be vaporized in quantity in excess of that which can be evaporated in its passage through the elements, means for insuring the distribution of the water to each element in an amount insufficient to fill the available cross-sectional area of said element, and means for delivering to the vapor generator the unevaporated liquid discharged from the elements.

20. Steam generating apparatus comprising in combination a steam generator, an auxiliary circuit connected thereto in which are included heating elements, means for maintaining a circulation producing pressure in the circuit, and means at the water inlet to the elements providing a pressure drop in the water entering the elements, whereby different degrees of pressure are maintained in the different parts of the circuit.

21. Steam generating apparatus comprising in combination a steam generator, an auxiliary circuit connected thereto in which are included heating elements, means for maintaining a circulation of water in the circuit, auxiliary heating means also in said circuit for heating with steam the water in circulation, and means for introducing steam into said auxiliary heating means.

22. Steam generating apparatus according to claim 21 in which also is included in the circuit means for separating from the water discharged from the heating elements any steam discharged therewith, and means for delivering said separated water to said auxiliary heating means.

23. Steam generating apparatus comprising in combination a steam generator, an auxiliary circuit connected thereto in which are included heating elements, means for circulating water through the circuit, means for variably delivering water from said circuit to the generator, auxiliary water heating means connected to the circuit, and means for delivering to said auxiliary water heating means the excess water flowing in the circuit and not delivered to the generator.

24. Steam generating apparatus comprising in combination a steam generator, an auxiliary circuit in which are included heating elements, means for circulating water through said circuit, means for feeding water from said circuit to the steam generator, and means operated in accordance with variations in the amount of water present in the circuit to control the amount of water circulated through the elements.

25. Steam generating apparatus comprising in combination a steam generator, an auxiliary circuit in which are included heating elements, means for circulating water through said circuit, means for introducing water into said circuit, means for feeding water from said circuit to the steam generator, and means arranged to control cooperatively the introduction of the water into the circuit and the feeding of the water to the steam generator.

26. Steam generating apparatus comprising in combination a steam generator, an economizer, means for feeding to the economizer at one end thereof the water to be evaporated and causing it to flow in the economizer uni-directionally in individual paths, means for positively distributing water to each of said individual paths, means for delivering to the steam generator the water heated in the economizer, and means for returning to the water inlet end of the economizer water discharged from the economizer in excess of that delivered to the steam generator.

27. The method of heating feed water for de-

- livery to a steam generator, which comprises delivering the feed water into heat exchanging relation to heating gases, positively distributing the water to a plurality of individual paths and 5 causing it to flow while in said heat exchanging relation uni-directionally in said paths so as to be progressively heated therein, delivering water to the steam generator after passage thereof out of said heat exchanging relation to replace that 10 evaporated in the steam generator, and returning for redelivery into said heat exchanging relation and for distribution and unidirectional flow in said individual paths any water in excess of that delivered to the steam generator.
- 15 28. The method of preheating a liquid for delivery to a vapor generator, which comprises causing the liquid to flow in heat exchanging relation to a source of heat while flowing in a circuit auxiliary to the vapor generator, causing liquid 20 to be delivered from said circuit to the vapor generator to replace the liquid evaporated in said generator, and effecting a positive distribution of the liquid to a plurality of individual paths for flow of the liquid therein while in said heat exchanging relation with said source of heat.
- 25 29. The method of preheating a liquid for delivery to a vapor generator, which comprises causing liquid from a source independent of the vapor generator to flow in heat exchanging relation to a source of heat through a positively defined path of liquid flow, limiting the amount of liquid flowing through said path with respect to the cross-sectional area available for flow in said path so that said liquid flow does not fill said cross-sectional area, and delivering to the vapor generator the heated liquid after discharge from flow through said positively defined path in said heat exchanging relation. 5
30. The method of preheating a liquid for delivery to a vapor generator, which comprises causing liquid from a source independent of the vapor generator to flow in heat exchanging relation to a source of heat through a positively defined path of liquid flow, limiting the amount of liquid flowing through said path with respect to the cross-sectional area available for flow in said path so that said liquid flowing in amount greater than in the evaporation thereof during its flow in said heat exchanging relation does not fill said cross-sectional area, and delivering to the vapor generator the heated liquid in excess of any evaporated while flowing in said path. 15 20 25

WALTER DOUGLAS LA MONT.
